CLAIM

The ornamental design for a surface configuration of a motorcycle, toy, and/or other replicas, as shown and described.

DESCRIPTION

FIG. 1 is a left, front perspective view of a surface configuration of a motorcycle, toy, and/or other replicas according to our novel design;

FIG. 2 is a left, rear perspective view of the surface configuration of a motorcycle, toy, and/or other replicas according to our novel design;

FIG. 3 is a right, front perspective view of the surface configuration of a motorcycle, toy, and/or other replicas according to our novel design;

FIG. 4 is a right, rear perspective view of the surface configuration of a motorcycle, toy, and/or other replicas according to our novel design;

FIG. 5 is a left side view of the surface configuration of a motorcycle, toy, and/or other replicas according to our novel design;

FIG. 6 is a right side view of the surface configuration of a motorcycle, toy, and/or other replicas according to our novel design;

FIG. 7 is a top view of the surface configuration of a motorcycle, toy, and/or other replicas according to our novel design;

FIG. 8 is a front view of the surface configuration of a motorcycle, toy, and/or other replicas according to our novel design; and,

FIG. 9 is a rear view of the surface configuration of a motorcycle, toy, and/or other replicas according to our novel design.

The broken lines are for illustrative purposes only and form no part of the claimed design.
